Inventor
Moses L. Hawks.

UNITED STATES PATENT OFFICE.

MOSES L. HAWKS, OF NEW YORK, N. Y.

NEEDLE-THREADER.

1,239,270.

Specification of Letters Patent. Patented Sept. 4, 1917.

Application filed January 19, 1917. Serial No. 148,346.

To all whom it may concern:

Be it known that I, MOSES L. HAWKS, a citizen of the United States, and a resident of New York city, borough of Manhattan, in the county of New York and State of New York, have invented certain new and useful Improvements in Needle-Threaders, of which the following is a specification.

- 10 This invention relates to needle threaders, and has for its principal object to provide a device of this character which is more efficient in operation than devices hitherto used and is more durable in use.
- 15 A further object is to provide in a device of this character, means whereby the needle threader proper may be concealed and entirely protected when not in use, and at the same time providing another instrument 20 which is useful wherever a needle threader is used.

The various further objects and advantages will more fully appear from the following detailed description and the features of novelty will be particularly pointed out in the claims.

In the drawing illustrating the invention,

Figure 1 is a plan view on an enlarged scale of the needle threader in its open or 30 operative position.

Fig. 2 is a section taken along line 2—2 of Fig. 1.

Fig. 3 is a plan view of the device as closed, illustrating the other instrument 35 afforded in the closed position.

Fig. 4 is a section on line 4—4 of Fig. 1.

In needle threaders as hitherto constructed, so far as I am aware, no means were provided for accurately bringing the 40 eye of the needle and the threading loop into accurate registration. Furthermore, the threading loop consisting of a thin wire or hook was in former constructions left unprotected, so that it could easily be bent or broken or otherwise rendered inoperative. 45 In my present invention these defects are overcome in a simple and effective manner, as will hereinafter appear.

Referring in detail to the drawing, the 50 threading loop 10 is mounted upon a support 11 which is formed preferably of sheet metal stamped out from a blank with various projections which are subsequently bent over to form the holding lugs 12 and 13 which anchor the ends of the loop 10 and the overhanging guard 14, disposed ad-

jacent to the vertex of the loop. A perforation 15 is formed in the plate 11 within the confines of the loop 10 through which perforation the thread 16 is passed (indicated in dotted lines in Fig. 2) during the threading operation. The threading loop 10, above referred to, is made of a thin spring wire sufficiently small in section to pass through the eye of the ordinary needle. 60 This wire is bent to form a vertex portion 17 from which the sides of the loop diverge to form the body of the loop about the aperture 15 and then contract to form a neck portion 18, and thence terminating in the 70 ends 19 preferably doubled back and anchored by the lugs 12 and 13. The extremity of the base 11 adjacent to the vertex 17 of the loop is bent over to form a guide portion 20 which serves to bring the eye 75 of the needle into accurate registration with the vertex of the loop. Thus, when the needle is to be threaded, it is merely grasped by the end, so that the eye is horizontal and then placed upon the guide 20 80 and shoved toward the vertex 17. The slant of the guide portion 20 is such that when the needle is brought adjacent to the vertex 17, the latter is exactly in registration with the eye of the needle, thus passing into the 85 eye as the needle is shoved from the position A to the position B in Fig. 1. The thread 16 is then passed through the aperture 15 and the needle is shoved back engaging 90 the thread and completing the threading operation.

The guard 14, as will be readily understood, serves to prevent the accidental bending of the loop away from the plane of the support and protects it from catching upon 95 other surfaces or objects either during the manipulation of the device or when it is held in the pocket or sewing machine drawer or elsewhere along with other articles as is usual with devices of this character.

When the threader is not in use, it may be further protected in the following manner: Pivoted to the base 11 by a suitable pivot such as an eyelet 21 is a sheath 22 which consists preferably of a bent-over U- 105 shaped strip of metal of a required length so that when the base 11 is swung over, it can enter into the U and be entirely covered thereby as illustrated in Fig. 3. While the device is in this position, a knife 23 formed 110 on the inner end of the base 11 and normally disposed at the interior of the sheath

22 (Figs. 1 and 2) is brought to the exterior as illustrated in Fig. 3 and thus may be used for cutting thread and button-holes or any other operation required during the course of sewing.

5 It will be understood, of course, that various modifications may be resorted to without departing from the spirit of the invention and the scope of the claims.

10 Having thus described my invention, I claim as new and desire to secure by Letters Patent:—

15 1. A needle threading device comprising a supporting member having an aperture through which the thread is passed, a resilient threading loop attached thereto and lying thereupon, and a guard portion extending from one edge of the supporting member and passing over the loop leaving 20 the opposite edge of the support free for the passage of the needle.

25 2. In a needle threading device, a supporting member having an aperture through which the thread is passed, a resilient threading loop attached thereto and lying thereupon, said loop having a vertex portion adapted to enter the eye of the needle, a body portion, a neck portion and diverging arms extending from the neck portion, and 30 the extremities of which are doubled back at a distance from the neck portion, and

lugs extending from the edges of the supporting member and bent over upon the extremities to anchor the loop in its proper position upon the supporting member.

35

3. A needle threading device comprising a supporting member having an aperture through which the thread is passed, a threading loop attached thereto and lying thereupon, a guide portion extending from the supporting member beyond the vertex of the loop, a guard passing over the loop adjacent the vertex, and a sheath member to which the support is pivoted, said support being movable so as to swing into the 45 sheath portion and be protected thereby, the guard portion serving to shield the loop from contact with the sheath, the end of the supporting member on the side of the pivot opposite to the needle threading means being formed as a knife which is 50 swung into position when the body of the supporting member is concealed in the sheath.

55

Signed at New York city, in the county of New York and State of New York, this 16th day of January, 1917.

MOSES L. HAWKS.
